[57] CLAIM

The ornamental design for a fresh cut Christmas tree stand waterer, as shown and described.

DESCRIPTION

FIG. 1 is a front elevational view of the fresh cut Christmas tree stand waterer showing my new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is a sectional view taken vertically through the mid-plane of the device at line 7—7 of FIG. 5.

The hose portion of the claimed design is shown broken away to indicate indeterminate length.

The broken line showing of a portion of a Christmas tree and stand is for illustrative purposes only and forms no part of the claimed design.
